US00D974395S

(12) **United States Design Patent** (10) Patent No.: **US D974,395 S**
Tuomey et al. (45) Date of Patent: ** Jan. 3, 2023

(54) **DISPLAY SCREEN OR PORTION THEREOF WITH GRAPHICAL USER INTERFACE**

(71) Applicant: **Aristocrat Technologies Australia Pty Limited**, North Ryde (AU)

(72) Inventors: **Thomas Tuomey**, Las Vegas, NV (US); **Jocellie Imutan**, Henderson, NV (US)

(73) Assignee: **Aristocrat Technologies Australia Pty Limited**

(**) Term: **15 Years**

(21) Appl. No.: **29/794,637**

(22) Filed: **Jun. 14, 2021**

Related U.S. Application Data

(62) Division of application No. 29/662,088, filed on Aug. 31, 2018, now Pat. No. Des. 925,552.

(51) **LOC (14) Cl.** **14-04**

(52) **U.S. Cl.**

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

The FIGURE is a display screen or portion thereof with graphical user interface showing our new design.

The dashed broken line perimeter in the FIGURE illustrates a display screen or portion thereof and forms no part of the claimed design. The remaining dashed broken lines in the FIGURE illustrate portions of the graphical user interface that form no part of the claimed design.
